BRUSH OR MIRROR BACK.

No. 20,174.

Patented Sept. 30, 1890.

UNITED STATES PATENT OFFICE.

RUDOLPH FUCHS, OF STATEN ISLAND, NEW YORK, AND GEORGE B. BEIDERHASE, OF JERSEY CITY, NEW JERSEY.

DESIGN FOR A BRUSH OR MIRROR BACK.

SPECIFICATION forming part of Design No. 20,174, dated September 30, 1890.

Application filed August 21, 1890. Serial No. 362,683. Term of patent 3½ years.

To all whom it may concern:

Be it known that we, RUDOLPH FUCHS, a citizen of the United States, residing at Staten Island, county of Richmond, State of New York, and GEORGE B. BEIDERHASE, a citizen of the United States, residing at Jersey City, in the county of Hudson and State of New Jersey, have invented and produced a new and original Design for Brushes, Mirrors, or other Toilet Articles; and we do hereby declare the following to be a full, clear, and exact description of the same, reference being had to the accompanying specification, forming a part thereof.

The design consists of a brush or mirror back having an ornamentation comprising the representation, of a central helix or circumvolution a and several smaller helices b branching therefrom or connecting therewith, and of numbers of fronds c and leaves d, branching from both the inner and the outer borders of the said helices or circumvolutions, the whole forming a design almost completely covering the surface to which it is applied, so that the interspaces f are quite small. The leaves and fronds of the design are veined, as shown at g.

When this design is applied to the back of a brush or hand-mirror having a handle, as shown in the accompanying photograph, a pendant o of the design extends down said handle.

The leading features of our design consist of the several connected helices or circumvolutions, fronds, and leaves brought in relief. 35

We claim—

The design for brushes, mirrors, and other toilet articles, substantially as herein shown and described.

In testimony whereof we affix our signatures 40 in presence of two witnesses.

RUDOLPH FUCHS.

GEORGE B. BEIDERHASE.
